UNITED STATES PATENT OFFICE.

FRED L. EBERHARDT, OF NEWARK, NEW JERSEY, ASSIGNOR TO GOULD & EBERHARDT, OF SAME PLACE.

DESIGN FOR A FRAME FOR SAND-SIFTERS.

SPECIFICATION forming part of Design No. 34,695, dated June 25, 1901.

Application filed May 16, 1901. Serial No. 60,617. Term of patent 14 years.

To all whom it may concern:

Be it known that I, FRED L. EBERHARDT, a citizen of the United States, residing at 17 Hillside avenue, Newark, county of Essex, 5 State of New Jersey, have invented a certain new and useful Design for the Frame of a Sand-Sifter, fully described and represented in the following specification and the accompanying drawings, forming a part of the same.

10 The present design relates to that class of machines in which a shaft is supported upon a frame and a rotatable sand-sifting screen is attached to one or both ends of the shaft, and the design is for the frame of such machine.

15 The design is illustrated in the annexed drawings, in which—

Figure 1 is a perspective view of the frame. Fig. 2 is a top plan view. Fig. 3 is an end elevation, and Fig. 4 is a side elevation.

20 This design comprises a stand supporting a vertical disk-like body *a*, having a tubular bearing *b* at the bottom, with an enlargement *b'* at the center, two flat seats *c*, projected

from opposite sides of the body below its center, and a flat seat *d* upon the top of the 25 body. The flattened circular body *a* is formed with rounded edges and a central opening *e*. The seat *d* is disposed chiefly at one side of the center line. The stand comprises a rectangular foot-plate *f*, having flanges *g*, which 30 extend up to the under side of the bearing *b*, and flanges *h*, which extend up to the under sides of the seats *c*.

The drawings clearly exhibit the entire design, and, 35

Having fully set forth the nature of the invention, what is claimed is—

The design for the frame of a sand-sifter, substantially as herein shown and described.

In testimony whereof I have hereunto set 40 my hand in the presence of two subscribing witnesses.

FRED L. EBERHARDT.

Witnesses:

THOMAS S. CRANE,
Jos. B. PIERSON.
